UNIDIRECTIONAL POWER SUPPLY

Madison Cawein, Fort Wayne, Ind., assignor to
Farnsworth Television and Radio Corporation,
a corporation of Delaware

Application January 11, 1943, Serial No. 471,976

6 Claims. (Cl. 171--97)

This invention relates to apparatus for generating direct current energy and particularly to apparatus for deriving high unidirectional voltages for use with cathode ray tubes.

According to conventional practice in the use of cathode ray tubes it is necessary to apply to certain of the electrodes of such a tube, unidirectional voltages of the order of several kilovolts. It has been proposed to rectify the periodic pulses of high potential resulting from the sudden current decay of a saw-tooth wave for the purpose of obtaining these high voltages. Typical apparatus of this type is disclosed in United States Patent No. 2,051,372 granted to Philo T. Farnsworth on August 18, 1936. By reason of certain limitations of the saw-tooth generator in the Farnsworth system, the oscillator generates saw-tooth waves having certain deficiencies. Not only is the current wave generated by the Farnsworth oscillator of limited amplitude, but the rate of change of the current from its maximum to its minimum value is such to effect the generation of a wave limited in its maximum frequency. This frequency is low enough to require the use of an iron core transformer for the coupling of the input and output circuits of the oscillator and also to require the use of relatively large filtering elements in the rectifier circuit.

Where it is necessary to generate a supply of high unidirectional voltage for use with cathode ray tube apparatus to be mounted in aircraft, it is important that the apparatus be made as light as possible. Accordingly, it should include a minimum number of iron core transformers and the filter condensers should be as small as possible.

An object of the present invention, therefore, is to provide an improved high unidirectional voltage power supply derived from apparatus which produces saw-tooth waves.

Another object of the invention is the provision of a higher unidirectional voltage power supply than heretofore obtainable and by means of lighter weight apparatus.

High voltage generating apparatus of the type disclosed by Farnsworth in the patent referred to has been modified by substituting a beam power tube for the tetrode used by Farnsworth. The substitution of the beam power tube for the tetrode produced results which were considerably beyond the scope of any reasonable expectancy and effected materially different and improved results over those previously obtainable with the original Farnsworth apparatus. There was found to be a substantial increase in the

magnitude of the generated saw-tooth current. The current decay from its maximum to its minimum value was found to be at a substantially higher rate, thereby enabling the generation of a higher frequency wave.

In accordance with the present invention there is provided an oscillator for generating periodic currents of saw-tooth wave form which includes an electronic device of the beam power type. 10 There is connected in the anode or output circuit of the tube an inductance. Regeneration or self-excitation for the oscillator is provided by another inductance loosely coupled to the above inductance. This other inductance is connected in the control grid or input circuit of the tube. The inductances are poled so that an increase in the anode current will apply a positive potential of such magnitude to the grid that the internal impedance of the tube is reduced to a relatively low value. A source of positive potential of predetermined magnitude is connected to the screen grid of the tube in series with an impedance. Such an oscillator functions to generate a periodic wave of substantially saw-tooth form. Frequencies of the order of 100 kilocycles per second may be obtained so that the coupling between the input and output circuits may be effected without the use of an iron core. Periodically, with the relatively rapid decay of the generated wave from 15 its maximum to its minimum value, there is produced at the anode of the tube a pulse of high voltage and of positive polarity. These high voltage pulses are rectified by a tube of the diode type and filtered. The resulting high voltage direct current may be applied to certain of the electrodes of a cathode ray tube.

For a better understanding of the invention, together with other and further objects thereof, reference is had to the following description taken 20 in connection with the accompanying drawing and its scope will be pointed out in the appended claims.

In the accompanying drawing:

Fig. 1 is a circuit diagram of a high voltage 25 generator embodying the present invention; and

Fig. 2 is a series of curves characteristic of voltages appearing in some of the circuits of Fig. 1.

Referring now more particularly to Fig. 1 of 30 the drawing, the generator embodying the present invention comprises an oscillator for the generation of saw-tooth waves and a rectifier. The oscillator includes a beam power tube 10 having a cathode 11, a control grid 12, a screen grid 13, beam-forming elements 14 and an anode 15. The

cathode 11 is connected internally of the tube to the beam-forming elements. Externally, the cathode is connected through a resistance 16 to the negative terminal of a source of direct current energy such as battery 17. The negative terminal of the battery is also connected to ground. The anode 15 of the tube is connected through an inductance 18 which forms the primary winding of an air-core transformer 19. The other terminal of the primary winding 18 is connected through resistances 20 and 21 to the positive terminal of the battery 17. The resistances 20 and 21 are by-passed to ground by condensers 22 and 23. The control grid 12 of the tube is connected through an inductance 24, forming a secondary winding of the transformer 19 to the negative terminal of the battery 17. The screen grid 13 of the tube is connected through a resistance 25 and resistances 20 and 21 to the positive terminal of the battery 17.

The anode 15 of the tube 10 is also connected to the anode of the diode rectifier tube 26. Heater current for the cathode of the rectifier tube is derived from an auxiliary winding 27 on the transformer 19. The cathode of the rectifier tube is connected to a shaping circuit including a series parallel connection of resistances 28, 29 and 30, and a condenser 31. The output of the rectifier tube 26 which is derived from the cathode is then connected through a relatively small filter condenser 32 to ground. Across the terminals of the condenser 32 is connected a voltage divider comprising resistance 33 and 34 and a potentiometer 35. The maximum voltage obtainable from the voltage divider is applied to the second anode 36 of a cathode ray tube 37 by a connection to the upper terminal of resistance 33. An intermediate unidirectional voltage, derived from the slider element 38 of the potentiometer 35, is applied to the focusing electrode 39 of the cathode ray tube. The control grid 40 and the cathode 41 of the cathode ray tube may be connected respectively to terminals 42 and 43 for the application of signaling voltages.

Considering now the operation of the apparatus illustrated in Fig. 1, reference will be made to certain observable characteristics of the oscillator before considering a suggested theory of operation which will be offered subsequently. Accordingly, the voltages which are known to exist at certain times in the various circuits associated with the elements of the beam power tube will be referred to. Such voltages are illustrated by the curves of Fig. 2.

The connection of the circuit of the control grid 12 to the resistance 16, introduces into this circuit a negative bias potential produced by the flow of cathode current through the resistance. However, the poling of the transformer windings 18 and 24 is regenerative so that, with an increase in the current through the primary winding 18, a positive potential derived from the secondary winding 24 is also introduced into the control grid circuit. During periods of current increase in the primary winding the positive potential is of sufficient magnitude to predominate over the negative potential and to thereby render the control grid sufficiently positive to reduce the impedance of the tube 10 to a relatively low value. During periods of current decrease in the primary winding a negative potential derived from the secondary winding is introduced into the control grid circuit which, in itself, is sufficient to increase to infinity the impedance of

the tube 10. There is also provided a positive bias for the screen grid 13 which is of predetermined minimum magnitude depending upon the value of the resistance 20, 21 and 25 and the voltage of the battery 17.

A cycle of operation will be assumed to start with the closing of the cathode-to-anode path within the tube 10. Current starts to flow in the series circuit comprising the battery 17, resistances 21 and 20, the transformer primary winding 18, the space current path of the tube 10, and the resistance 16. The impedance of the anode-to-cathode path within the tube constitutes the major part of the resistance portion of the circuit. Consequently, the impedance of resistances 16, 20 and 21 may be neglected for the present purpose. By reason of the inclusion of the inductive primary winding 18 in this circuit, the current increase with respect to time is gradual. During the time that the current is increasing in this circuit, the potential of the cathode 11 of the beam power tube 10 is becoming more positive, as indicated by the curve 44 of Fig. 2. At the same time, the potential applied to the screen grid 13 of the tube is becoming increasingly positive, as indicated by the curve 45. Concurrently with these voltage changes, the voltage of the anode 15 of the tube remains at a substantially constant negative value, as indicated by the curve 46. Also the potential applied to the control grid 12 similarly remains at a substantially constant value which is positive, as indicated by the curve 47. These conditions exist for a period of time which, it has been found, is determined primarily by the ratio of the inductance external of the tube 10 to the internal resistance of the tube, included in the series anode-to-cathode circuit of the tube. The current increase between the cathode and anode of the tube 10 suddenly stops and a sharp decrease in this current ensues. A complete interruption of the current flow is effected in considerably less time than in prior art devices, such as the Farnsworth oscillator.

At this point the anode voltage rises momentarily to a sharp positive peak indicated by the curve 48. This high voltage pulse is produced by the steep wave front portion of the saw-tooth wave. The amplitude of this peak is considerably in excess of the voltage of the battery 17. Also, at this time, the potential of the control grid 12 is momentarily reduced to a high negative value which is in excess of the negative biasing effected by the self-biasing resistance 16. This momentary negative potential is represented by the curve 49. Coincidentally with the appearance of these potential peaks, the positive potential of the screen grid 13 rises sharply to a value which is substantially equal to that of the battery 17. This potential change is indicated by the curve 50. Also, the potential of the cathode 11 is suddenly reduced to zero, as indicated by the curve 51. The potentials represented by the curves 48, 49, 50 and 51 exist only for the short period of time that the cathode-to-anode current is interrupted. The potentials of the tube elements then revert to their initial polarities and values, resulting in the reclosing of the cathode-to-anode path within the tube 10 and the repetition of the described cycle.

From the curves of Fig. 2, it is seen that, during the major portion of the cycle, the control grid potential has a substantially uniform value while the cathode potential has an increasing value. It is readily seen, therefore, that the po-

tential between these tube elements has a complex wave form which is substantially a saw-tooth form, as indicated by the curve 52.

The frequency of the current wave produced by the oscillator embodying the present invention, is determined primarily by the ratio of the external inductance represented by the primary winding 18 of the transformer 19, to the internal resistance of the tube 10. These frequency-determining facilities are substantially different from the facilities provided for a similar purpose in the oscillator disclosed in the Farnsworth patent referred to. In the Farnsworth oscillator, the frequency control is effected by adjusting the value of the grid leak resistance connected from the control grid to ground. In the oscillator, in accordance with the present invention, variation in the frequency of the generated current wave may be effected conveniently by varying the value of the resistance 16 which thereby changes the bias of the control grid 12. Thus, the internal resistance of the tube is changed, thereby altering the inductance-to-resistance ratio of the cathode-to-anode series circuit. It has been found that the actual impedance of the primary and secondary transformer windings 18 and 24 respectively, are not at all critical for the successful operation of the oscillator.

The value of the resistance 16 determines the amplitude of the high peaks or pulses of anode voltages produced by the operation of the present oscillator, and also controls the speed of the generated current wave. The latter control determines the time required for the generated current wave to change from its maximum to its minimum value. It has been found that for every design of an oscillator of this type there are certain optimum values of impedance and positive potential connected to the screen grid 13.

The apparatus connected in the manner described and illustrated in Fig. 1, has been found to give satisfactory results for the purposes described when using circuit elements and constants in accordance with the following table. The oscillator frequency is approximately 100 kilocycles per second and the direct current voltage is approximately 1500 volts.

Tube 10	12A6
Resistance 16	100 ohms
Battery 17	250 volts
Primary winding 18	25 millihenries; 500 turns
Resistances 29 and 31	1000 ohms
Condensers 22, 23 and 31	.005 microfarad
Secondary winding 24	1 millihenry; 100 turns
Resistance 25	6000 ohms
Tube 26	12H6 (1/2)
Heater winding 27	10 turns
Resistance 28	0.1 megohm
Resistances 29, 30 and 34	0.47 megohm
Condenser 32	250 micromicrofarads
Resistance 33	0.94 megohm
Potentiometer 35	0.2 megohm

It is believed that a fuller appreciation of the marked distinction of the oscillator included in the present invention over prior art oscillators may be derived from a consideration of the following suggested theory of operation. It seems evident from a study of the curves of Fig. 2, that the interruption of the cathode current, once it is started, is accelerated at such a high rate that the current cut-off is relatively absolute. The acceleration is apparently caused by the negative impulsive potential of the control grid 12, as indicated by the peak 49. This potential is devel-

oped by the regenerative coupling of the transformer windings 18 and 24 in response to the slight lessening of the rate of increase of the cathode current. Up to a certain point, this rate of increase is constant. As the cathode current starts to increase, it is seen from the curve 45 that the potential of the screen grid 13 is at its lowest value. This is probably due to the deflection of a large number of electrons toward the screen grid at this time. As the cathode current increases, the potential of the cathode also increases, as evidenced by the curve 44. The potentials of the beam-forming electrodes 14 also increase similarly since they are connected internally of the tube to the cathode 11. It appears likely that, as the potentials of the beam-forming electrodes increase, the number of electrons which are deflected toward the screen grid decreases at the same rate until the potential of the screen grid reaches a value at which a part of the electron beam strikes the beam-forming electrodes. This action initiates interruption of the cathode current which then, because of the regenerative action of the device, completely ceases substantially instantaneously.

By use of the apparatus arranged in the manner described, it is possible to obtain advantageous results which have hitherto been impossible to obtain. The use of the beam power tube in the oscillation generator produces larger currents of saw-tooth wave form. The change of the saw-tooth wave from its maximum to its minimum value is accomplished in a shorter time than heretofore possible, thereby producing a steeper wave front of this portion of the saw-tooth wave. These two effects permit the generation of higher frequency saw-tooth waves and also produce higher voltage anode pulses. By reason of the higher frequencies obtainable it is possible to secure adequate regenerative coupling between the input and output circuits of the oscillator tube without the use of an iron-core transformer. Also, the higher frequency waves require the use of much smaller filter condensers. The higher frequency waves, together with the higher voltage anode pulses, permit the production of a higher voltage direct current. The ultimate effect of all of these improved results is the production of a higher unidirectional voltage by the use of extremely light weight apparatus.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A unidirectional voltage supply system comprising, an oscillator for generating currents of saw-tooth wave form, said oscillator including an electronic device having input and output circuits and a predetermined normal internal resistance, an external circuit coupled to said output circuit including an inductance, an external circuit coupled to said input circuit including a second inductance regeneratively coupled to said first inductance, said electronic device being a tube of the beam power type whereby the frequency of the generated wave is determined by the ratio of said output circuit inductance to said internal resistance, and means including a rectifier directly coupled to said output circuit for

converting the voltage pulses produced by the steep wave front portions of said saw-tooth wave to a unidirectional voltage.

2. A unidirectional voltage supply system comprising, a direct current supply source, an air-core transformer having inductively related primary and secondary windings, an oscillator for producing currents of saw-tooth wave form, said oscillator including a beam power tube having input and output circuits and an auxiliary electrode connected to the positive terminal of said low voltage source, said primary winding being connected to said direct current supply source and to said output circuit, said secondary winding being connected to said input circuit, and unidirectional conducting means directly coupled to said output circuit for converting the voltage pulses produced by the steep wave front portions of said saw-tooth wave to a unidirectional voltage.

3. A unidirectional voltage supply system comprising, a direct current supply source, a magnetically coupled oscillator for producing currents of saw-tooth wave form, said oscillator including a beam-power tube having input and output circuits and an auxiliary electrode connected to the positive terminal of said direct currents supply source, a primary inductance connected to said direct current supply source and to said output circuit, a secondary inductance regeneratively coupled to said primary inductance, said secondary inductance being connected to said input circuit, and means connected to the output circuit of said tube and including a filter condenser for converting the voltage pulses produced by the steep wave front portions of said saw-tooth wave to a unidirectional voltage.

4. A unidirectional voltage supply system comprising, a direct current supply source, an oscillator having inductively coupled input and output circuits for producing currents of saw-tooth wave form, said oscillator including a beam-power tube having a cathode, an anode, a control grid and an auxiliary electrode, means for maintaining said electrode at a positive potential, an output circuit inductance connected to said direct current supply source and to said cathode and said anode, an input circuit inductance regeneratively coupled to said output circuit inductance, said input

circuit inductance being connected to said cathode and said control grid, means connected to said anode for rectifying the voltage pulses produced by the steep wave front portions of said saw-tooth wave, and a condenser connected to filter said voltage pulses to produce a unidirectional voltage.

5. A unidirectional voltage supply system comprising, a direct current supply source, an oscillator having inductively coupled input and output circuits for producing currents of saw-tooth wave form, said oscillator including a beam-power tube having a cathode, an anode, and two grid electrodes, a connection from the positive terminal of said direct current supply source to a first one of said grid electrodes, an output circuit inductance connected to said direct current supply source and to said cathode and said anode, an input circuit inductance loosely coupled regeneratively to said output circuit inductance, said input circuit inductance being connected to said cathode and the second of said grid electrodes, a rectifier connected to said output circuit for conducting the voltage pulses produced by the steep wave front portions of said saw-tooth wave, and a condenser connected to said rectifier for filtering said voltage pulses to produce a unidirectional voltage.

6. A unidirectional voltage supply system comprising, a direct current supply source, an oscillator having inductively coupled input and output circuits for producing currents of saw-tooth wave form, said oscillator including a beam-power tube having a cathode, an anode, a control grid and a screen grid, a connection from the positive terminal of said direct current supply source to said screen grid, an output circuit inductance connected to said direct current supply source and to said cathode and said anode, an input circuit inductance loosely coupled regeneratively to said output circuit inductance, said input circuit inductance being connected to said cathode and said control grid, a rectifier connected to said anode for conducting the voltage pulses produced by the steep wave front portions of said saw-tooth wave, and a condenser connected to said rectifier for filtering said voltage pulses to produce a unidirectional voltage.
